Primary Examiner—Mimosa De
(74) *Attorney, Agent, or Firm*—Calfee, Halter & Griswold LLP(57) **CLAIM**

I claim the ornamental design for a cabinet, as shown and described.

DESCRIPTION

FIG. 1 is a front perspective view of a cabinet showing the new design;

FIG. 2 is a front view of the cabinet of FIG. 1;

FIG. 3 is a rear view of the cabinet of FIG. 1;

FIG. 4 is a left side view of the cabinet of FIG. 1;

FIG. 5 is a right side view of the cabinet of FIG. 1;

FIG. 6 is a top view of the cabinet of FIG. 1; and,

FIG. 7 is a bottom view of the cabinet of FIG. 1.

The broken lines shown in the drawings are for illustrative purposes only and form no part of the claimed design.
